WILLIAM J. GUSTIN, OF INDIANAPOLIS, INDIANA; LEO. L. GUSTIN ADMIN-
ISTRATOR OF SAID WILLIAM J. GUSTIN, DECEASED.

FOOT-POWER RIVETING-MACHINE.

1,186,169.

Specification of Letters Patent.

Patented June 6, 1916.

Application filed November 4, 1913. Serial No. 799,230.

To all whom it may concern:

Be it known that I, JAMES C. BURGESS, a citizen of the United States, and residing at Indianapolis, in the county of Marion and State of Indiana, have invented certain new and useful Improvements in Foot-Power Riveting-Machines, of which the following is a specification, reference being had to the accompanying drawings and to the letters and figures of reference marked thereon.

My invention relates to the type of riveting machine that is especially adapted for use in jobbing shops and small factories, more particularly for rapidly riveting thin sheets of metal together, and which is specially adapted for foot-power operation.

An object of the invention is to provide a riveting machine of inexpensive construction which shall be reliable, durable and economical in use.

Another object is to provide a foot-power riveting machine of such construction as to conveniently make use of rivets for punching holes in the sheets to be secured together by the rivets.

A further object is to provide a riveting machine of improved construction that can be so operated and controlled as to permit the operator to use his hands solely in handling and manipulating the material to be worked on and without necessitating frequent handling of the rivets, an aim being to provide a riveting machine with means for automatically feeding the rivets to the work.

With the above-mentioned and other objects in view, the invention consists in a machine having certain novel features of construction, improved elements, and combinations and arrangements of parts, as hereinafter particularly described and further defined in the accompanying claims.

Referring to the drawings, Figure 1 is a side elevation of the improved riveting machine partially in section; Fig. 2 is a fragmentary front elevation of the machine or as viewed from the plane of the line 2—2 on Fig. 1; Fig. 3 is a fragmentary section approximately on the line 3—3 on Fig. 1; Fig. 4 is a fragmentary sectional elevation approximately on the line 4—4 on Fig. 1; Fig. 5 is a side elevation of the machine

partially in section to show the riveting devices in operation; Fig. 6 is a fragmentary sectional elevation on an enlarged scale of coöperating parts as they appear in Fig. 5 but slightly modified as to one of the parts; and, Fig. 7 is a fragmentary sectional plan looking downward from the plane of the line 7—7 on Fig. 6.

Similar reference characters on the different figures of the drawings indicate corresponding elements or features of construction herein referred to.

As preferably constructed the machine is provided with a suitable supporting frame 1 and a table 2 thereon. An arm 3 is rigidly fixed on the normal rear portion of the table and extends upwardly and forwardly above the forward portion of the table, the top of the arm near the forward end thereof having a fulcrum stand 4 thereon provided with a pivot 5. The forward end of the arm is provided with a guide-head 6 having a cap 7 thereon. A header 8 of novel construction is provided which is vertically guided in the guide-head above the forward portion of the table and is provided with a device 9 that directly engages and controls the header. The bottom or under face of the header has a socket 10 therein to receive the end of a rivet, the bottom of the header having also a concave depression 11 adapted for upsetting the ends of the rivets. In some cases the depression is in a slightly projecting heel formed on the bottom of the header, as shown in Figs. 1 and 5, to constitute a guide against which to place work to be riveted; in other cases the header has a plane surface on its bottom, as in Fig. 6. A pivot 12 is carried by a lever 13 which is mounted on the pivot 5 and in the present case fixed to the device 9 so that the lever moves and controls the header. Preferably the device 9 is rounded on its top and bottom and operates in an opening formed in the header. A connecting rod 14 is connected to the pivot 12 and has a pivot 15 connected thereto to which is connected a controlling lever 16 that is supported on a pivot 17 mounted on the frame 1. The lever 16, as will be seen, is supported between its ends and is provided with a pivot 18 between its forward end and its supporting pivot 17. A connecting rod 19 is provided which is

105

relatively shorter than the connecting rod 14 and is connected to the pivot 18 and extends upward therefrom, the upper portion of the connecting rod 19 being provided with a pivot 20 to which a punch ram lever 21 is connected, the latter being mounted on a pivot 22 suitably supported below the table 2. The lever 21 being horizontally arranged and supported between its ends it extends forward beyond its support and has a horizontal slot 23 therein that receives a pivot 23 that is provided on the lower end of a ram 24 which is vertically guided in the table 2 and so as to be projected into a guideway 25 after passing a rivet-stop 26 fixed on the table 2 at the end of a feed-channel, the ram being adapted to lift the rivets from the feed-channel and through the guideway 25 to metal sheets 27 placed upon an anvil bar 28 mounted on the table 2 and in which the guideway 25 is conveniently arranged. The header is movable downward nearly to the anvil bar so as to force the plates 27 on the anvil bar, and as will be seen the ram 24 is in alinement with the socket 10.

The lever 16 which operates and controls the header lever 13 and the ram lever 21 may be operated and controlled by various power means, as is obvious, the forward portion of the lever 16 preferably being provided with a pivot 29 to which a link 30 is connected, the latter having a pivot 31 connected thereto with which a foot-lever 32 is connected between its ends, one end of the foot-lever being connected to a pivot 33 supported by the frame 1 of the machine. A retracting-spring 34 is connected to the foot-lever and also to the frame, and the forward portion 40 of the foot-lever has a treadle or foot-plate 35 thereon.

For automatically feeding the rivets forward on the table to the rivet-stop 26 a feed-rod 36 is provided which is arranged horizontally on the table and provided with a sheave 37 about which a cord or cable 38 is placed, one end of the cord being secured to an eye 39 with which the under side of the arm 3 is provided, the cable extending downward through the table over a guide sheave 40 that is supported under the table. The lower end of the cord is provided with a weight 41 that acts to move the feed-rod forward, the latter being readily retracted by hand. Preferably the anvil bar 28 is composed of sections secured upon the table 2 by means of screws 42, and a guide channel 43 is conveniently provided in the under side of the anvil bar to guide the rivets on their heads and receive the feed-rod 36, the latter being provided with guides 44 mounted on the table 2. The top of the table has a groove 45 therein in which the sheave 37 operates, and a slot 46 extends from the groove and through which the

cord 38 operates. In the feed-channel 43 are horizontal guide bars 47 between which the bodies of the rivets are guided while the heads of the rivets pass under the guide bars.

In practical use the feed-rod 36 is retracted by hand and a quantity of rivets placed in the feed-channel by hand, after which the feed-rod is placed against the rearmost one of the rivets in contact with the head thereof, the rivets being placed 70 with their heads downward, the foremost one of the rivets being stopped against the rivet-stop 26 and upon the top of the ram 24 which is at rest position while the header is in retracted elevated position, as indicated 75 in Fig. 1. The sheets that are to be riveted together are placed upon the anvil bar 28 and, force being applied to the treadle 35 the various levers are caused to move, with the result that the header 8 is brought down 80 upon the plates 27 and the ram 24 caused to force a rivet upward through the plates and into the socket 10, as seen in Fig. 5, after which the ram and the header are permitted to be retracted through the action of the 85 spring 34. The sheet containing the rivet, the end of the latter being withdrawn from the socket, is shifted to bring the end of the rivet under the depression 11, after which the treadle is again operated and the header 90 forced down so as to upset the rivet and form another head thereon in the depression 11, thus securing the plates together, and at the same time if a rivet is placed upon the ram 24 it is forced through other portions 95 of the plates, as in Fig. 6, so that the work 100 is performed rapidly.

Having thus described the invention, what is claimed as new is—

1. A riveting machine including a supported anvil bar having a vertical guideway therein, a header guided to be moved downward and hold metal sheets upon the anvil bar and having a socket in its bottom in alinement with the guideway, a ram vertically guided to be moved upward into the guideway and adapted to carry a rivet upon its top with the end of the rivet uppermost, and means for moving the ram to force the end of the rivet to punch a hole in the sheets 115 and enter the socket.

2. A riveting machine including a table horizontally supported and having a feed-channel thereon and also an anvil bar extending over the feed-channel, the anvil bar having a vertical guideway therein, a rivet-stop on the table to stop a rivet below the guideway, an arm fixed upon the table and having a guide head thereon above the anvil bar, a header vertically guided in said head 120 and having a socket in its bottom alining with the guideway, a lever pivotally mounted upon the top of the arm and connected to the header to move the latter downward and hold metal plates upon the 125 130

anvil bar, a punch lever pivotally supported under the table, and a ram connected to the punch lever and vertically guided in the table to carry the rivet into the guideway 5 and force the end of the rivet through the sheets and into said socket.

3. In a foot-power riveting machine of the class described, a frame, a metal plate supported on a plane surface of the frame, 10 means for connecting said plate to said frame, a punch ram, a horizontal punch lever, means for connecting the punch ram to the end of the punch lever, a horizontal header lever, means for connecting the horizontal 15 header lever to the punch lever, a foot-lever, and a vertical header connected to the end of the horizontal header lever, the punch lever and the header lever being so constructed and arranged as to be simultaneously 20 operated by a downward movement of the foot-lever.

4. In a riveting machine, the combination with a frame and a table thereon, of an arm fixedly secured to the top of the table and 25 having a fulcrum stand on the top thereof, the arm having also a guide head on its end, a header vertically guided in the guide head and having a socket in its bottom, a header lever, pivoted to the fulcrum stand and connected to the lever, a punch lever pivotally supported under the table, a punch ram connected to the punch lever and guided in the table in alinement with said socket, and a horizontal feed-channel for guiding rivets 30 with their heads undermost onto the top 35 of said ram to be carried thereby upward and partially into said socket.

5. In a riveting machine, the combination of a horizontal table, an anvil bar mounted upon the table and having a vertical guideway therein and also a horizontal feed-channel leading to the guideway for guiding rivets standing on their heads, a header movable vertically downward to hold metal 45 sheets upon the anvil bar, means for advancing and retracting the header, a ram guided in the table for vertical movement upward into the guideway, the ram being adapted to receive and carry a rivet from 50 the feed-channel through the guideway to the header, a rivet-stop supported at the end of the feed-channel to stop a rivet upon the ram, and means for controlling the ram and forcibly moving it upward to lift the

rivet thereon and force the upper portion of 55 the rivet through the metal sheets to punch a hole for the rivet.

6. In a riveting machine, the combination of a table having a groove in its top and a slot extending through the table from 60 the groove, an arm secured to the top of the table and extending above the groove, a guide sheave supported under the table adjacent to one end of the groove, a feed-channel for rivets horizontally arranged 65 upon the table, a header mounted on the arm above the end of the feed-channel, a feed-rod movable in the feed-channel and having a sheave thereon arranged in said groove, a cord connected at one end to said 70 arm and extending about the feed-rod sheave and thence downwardly through said slot and over said guide sheave, a weight secured to the opposite or lower end of said cord, and a ram movably guided in the table 75 for vertical movement to receive the rivets from the feed-channel and force them up to the header.

7. In a foot-power riveting machine, the combination of a frame, a table on the frame, an arm secured to the top of the table, a header guided vertically on the end of the arm, a horizontally arranged header lever pivoted to the arm and connected to the header, a connecting-rod pivoted to the 80 header lever, a horizontal punch lever pivotally supported under the table, a punch ram pivotally connected to the punch lever and vertically guided in the table below the header for carrying rivets upward to the 85 header, a relatively short connecting-rod pivoted to the punch lever, a controlling-lever pivotally connected to the said connecting-rods and pivotally supported between said connecting-rods on the frame 90 below the table, a foot-lever pivoted to the frame below said controlling-lever, a link connected to said foot-lever and said controlling-lever, and a spring connected to the frame and said foot-lever to draw the 100 foot-lever upwardly.

In testimony whereof I hereunto set my hand in the presence of two subscribing witnesses.

JAMES C. BURGESS.
